UNITED STATES PATENT OFFICE.

JACOB A. HYLE, OF PHILADELPHIA, PENNSYLVANIA, ASSIGNOR TO AMERICAN RAIL JOINT COMPANY, A CORPORATION OF DELAWARE.

RAILWAY-RAIL JOINT.

Application filed December 9, 1922. Serial No. 605,757.

To all whom it may concern:

Be it known that I, JACOB A. HYLE, a citizen of the United States, residing at Philadelphia, in the county of Philadelphia and State of Pennsylvania, have invented certain new and useful Improvements in Railway-Rail Joints, of which the following is a specification.

This invention relates to a novel improvement in railway rail joints, and has special reference to the construction of the rail joint bars or plates, whereby the clamping effect against the track rails at and near the meeting ends of the rails is more readily facilitated and adapted to compensate for the wear which usually occurs at and near said meeting ends.

The prime object of this invention is to provide novel, simple, durable, economical and thoroughly efficient means for safely and reliably uniting and securing the meeting ends of railway track rails together, said means serving to materially increase the longevity of the rail joint and track rails.

A further object of the invention is to provide a safe and reliable railway rail joint composed of a minimum number of parts, with means for firmly securing the several parts together when properly assembled, said joint including novel means adapted to compensate for the wear which customarily occurs at and near the juncture of the meeting ends of the track rails.

Another object of the invention is to so construct my improved rail joint that the meeting ends of the track rails will always possess a maximum amount of vertical strength, together with a maximum of lateral strength and rigidity to withstand the enormous strain to which the rails are subjected during the travel of the heavy rolling stock thereon.

Further objects of the invention are to so construct each rail joint splice bar or plate that if broken it will be impossible for the broken parts of said bar or plate to work outwardly and thus become a dangerous factor during the movement of the rolling stock thereover; to so construct each splice bar or plate that its outer face will be clamped by a wedge-shaped member throughout its length; that the upper reinforced portion of each splice bar or plate will be caused to be readily flexed in contact with

the lower surface of the rail tread and the upper end portion of the web of the rail at and near the meeting ends of the rails, by the proper adjustment of the wedge-shaped member fitted therein and simultaneously cause the lower reinforced portion of each splice bar or plate to securely clamp against the upper surface of the base of each rail and the lower portion of the web of the rails; to construct each splice bar or plate from a single piece of metal formed with an excess of metal at its head and foot portions, and thickened at the portion where the rail tread merges into the web and where the web merges into the rail base, and comparatively thin intermediate portions connecting said head and foot portions adapted to yield when the wedge member is drawn or forced inwardly thereby causing the said splice bars or plates to snugly and securely contact with the web, tread and base of each rail; to so construct each wedge member with an excess of metal at its upper and lower portions that its strength and durability is materially increased, and with means coacting with means provided in the construction of the splice bars or plates, that the coaction between said bars or plates and the wedge-members readily facilitates compensation for the wear of the rails at and near their meeting ends, and to provide means for insulating the track rails from the joint members.

The foregoing and such other objects as may appear from the ensuing description are accomplished by the construction, arrangement, location and combination of the parts hereinafter more fully described, illustrated in the accompanying drawings, and particularly pointed out in the claims appended hereto, it being understood that slight changes in the precise form, proportions and minor details of the construction may be resorted to without departing from the spirit or sacrificing any of the advantages of the invention.

In the accompanying drawings which form a part of the specification it will be seen that:

Figure 1 is a perspective of the novel railway rail joint embodying my invention.

Fig. 2 is a transverse section taken in the plane of the dotted lines 2—2, Fig. 1.

Fig. 3 is a transverse section taken in the

plane of the dotted lines 3—3, Fig. 1, showing means for insulating the track rails from the joint plates.

Fig. 4 is a side elevation of the outer face of one of the splice bars or plates shown in Figs. 1, 2 and 3, disconnected from the joint.

Fig. 5 is a cross-section taken in the plane of the dotted lines 5—5, Fig. 4.

Fig. 6 is a side elevation of the outer face of one of the wedge-members removed from the joint, and

Fig. 7 is a cross section taken in the plane of the dotted lines 7—7, Fig. 6.

In the embodiment of my invention as illustrated, it will be seen by reference to Fig. 1, that the track rails 1 and 2 are shown as being connected together by the splice bars or plates 3, each of said bars or plates being rolled from a single piece of steel, each of said bars or plates 3 being formed with an elongated slotted opening 4 adjacent its head or upper portion, extending the major portion of its length, and a similar elongated opening 5 adjacent its foot or lower portion for the purpose hereinafter described. Each bar or plate 3 is provided with an upper head member 6 formed with an excess of metal thickened or enlarged at 7, and is so shaped as to rest snugly and closely in contact with and clamp the under surface of the rail tread and the upper portion of the web of the rail, while the foot or lower member 8 of said bar or plate is also formed with an excess of metal reinforced at 9, and so shaped as to tightly contact with and clamp the upper surface of the base of the rail and the lowermost portion of the web of the track rail, the web portion 10 of said splice bar or plate being rolled comparatively thin for the purpose hereinafter referred to.

It will be observed that the outer face of each splice bar or plate 3 forms a wedge-shaped recess 11 for the reception of a wedge-shaped member 12 which is fitted within said recess overlapping the web portion of said bar or plate 3, and extending throughout the length of the said bar. Each wedge-shaped member is provided at its head and foot portions with an excess of metal 13 adapted to materially add to its strength and durability, and is formed with four central openings therethrough for the reception of the securing bolts 14, each bolt being passed through similar openings formed through the track rails and splice bars or plates and adapted to register, and securely fitted to the threaded end of each bolt is a securing nut 14' adapted to contact with the outer face of the wedge-members, said nuts being fitted so as to alternate on opposite sides of the joint. Each wedge member is also provided with a recessed inner face, said face terminating at both its upper and lower portion with an integral inward extension 15 so formed that the ex-

tensions 15 may readily enter the slots 4 and 5 of each splice bar or plate.

It will be perceived that when the joint wears at and near the meeting ends of the rails by turning the nuts inwardly on the two bolts nearest said meeting ends, the wedge members will be forced inward into the recess 11 and the extensions 15 of said members will be caused to enter the slots formed through the splice bars, thereby forcing the splice bar to yield in its thinnest web portion, and simultaneously cause the reinforced head and foot portions of the splice bars which are acted upon by said extension 15 to be flexed rigidly and tightly into contact with the upper surface of the rail bases, respectively. Thus more direct strength is assured, and when the splice bars are away from the rail treads, and since expansion and contraction cause wear the splice bars may be forced closer to the rails from time to time as occasion may require by the wear at and near the meeting ends of the rails, while the clamping effect of the bars and wedge-members is not so intense at and near the ends thereof, hence the wave motion of the track rails, usually caused by travel of the rolling stock thereon, may pass through the joint to the rail ends, thereby lessening and practically eliminating the tendency of the breakage of the track rail in a plane with one or more of the bolt holes formed nearest the meeting ends of the rails, thereby creating an annual saving of a considerable amount to the railway system.

It will be seen that each splice bar or plate is thickened or reinforced at the points 7 and 8, thus forming a dovetail like portion between said points and the outer side of the splice bar, which together with the clamping effect of the wedge members against the outer face of the head and foot portions of the splice bars and the securing bolts passing through said splice bars, renders it practically impossible for a portion of the splice bar to work outwardly, either sidewise or endwise, in the event that said bar shall have become broken, thereby preventing such broken part from causing a dangerous menace and obstruction.

By my improved construction the battering of the ends of the rails is entirely eliminated by forcing the wedge-members inwardly at and near the meeting ends of the rails, thereby causing the inner extensions 15 of said members to enter the slots 4 and 5 of the splice bars and thus spreading, flexing, expanding or bowing upwardly such portions of the splice bars as are disposed at and near the juncture of the track rails into close and rigid contact with the worn portions of the rails, thus lessening the clamping effect at and near the outer ends of the joint and permitting the wave motion of the rail to continue to the lower

portion of the splice bars, which is substantially at the end of the track rail, thereby avoiding the usual tendency of the breakage of the rail at one or the other of the bolt holes near its ends.

It will also be evident that the forcing of the wedge-members inwardly at and near their central portions will cause the extensions 15 to register with and to gradually

10 enter the slots 4 and 5 of the splice bars, and from time to time, as the wear occurs, it can be readily compensated for by again forcing the wedge members inwardly, which action correspondingly flexes the head and foot 15 portions of the splice bars into contact with the worn portion of the rail, and that such adjustment of the wedge-members will cause the securing nuts to remain under tension at all times.

20 It will be understood by this construction of rail joint the ordinary rail spikes such as shown at 16 are employed for fastening the track rails to the usual railway ties and that said joint may be used with or 25 without the use of railway joint cross-ties to support or suspend it.

By reference to Fig. 3 will be seen the means of insulating my improved joint, which consists in placing a single sheet of 30 plate or insulating fibre 17, between each inner face of the splice bars and the track rails, said sheet extending throughout the length of each splice bar, and a sleeve 18 of insulating fibre passed through each bolt 35 opening in the track rails and surrounding each bolt, and since the greatest wear upon the insulation will occur upon those portions which rest at and near the meeting ends of the track rails, each sheet or plate 17 of the fibre may be so constructed that they can be 40 reversed edge for edge the entire length of the joint, thereby practically doubling the longevity of the insulation.

Having thus described my invention, what 45 I claim and desire to secure by Letters Patent is:

1. A rail joint of the character described, comprising track rails, a splice bar formed with a recess within its outer face and a slot 50 cut therethrough at each side of its longitudinal central portion, and means fitted within said recess and slots for causing the upper and lower portion of said splice bar to be flexed against the rail tread and rail base, respectively.

2. A rail joint of the character described, comprising track rails, a splice bar formed with a recess within its outer face and a slot 55 cut therethrough at either side of its longitudinal central portion, and a wedge member fitted within said recess and formed with inward extensions engaging said slots and adapted to cause said splice bar to be flexed against the rail tread and rail base 60 respectively.

3. A rail joint of the character described, comprising track rails, a splice bar formed with outwardly extended head and foot portions and a recess within its outer face, said splice bar having longitudinal slots formed therethrough at each side of its central portion, and a wedge-shaped member fitted within said recess and slots adapted to cause the splice bar to be flexed against the lower face of the rail tread.

4. A rail joint of the character described, comprising track rails, a splice bar formed with reinforced head and foot portions and a longitudinal slot formed therethrough adjacent both the head and foot portions, and a wedge-shaped member fitted into the outer face of said splice bar and provided with inward extensions adapted to engage said slots and flex said head and foot portions tightly against the track rails.

5. A rail joint of the character described comprising track rails, a splice bar formed with reinforced head and foot portions having a longitudinal slot formed therethrough adjacent both the head and foot portions and a recessed outer face, and a wedge-shaped member fitted within said recess and provided with inward extensions formed on its inner face at its upper and lower portions, said extensions being adapted to enter said slots and flex said head and foot portions tightly into contact with the track rails.

6. A rail joint of the character described comprising track rails, a splice bar formed with reinforced head and foot portions having a longitudinal slot cut therethrough adjacent both the head and foot portions and a recessed outer face, said slots extending the major portion of the length of said bar, and a wedge-shaped member, fitted within 105 said recess, reinforced at its upper and lower portions and its inner face being provided with an inward extension at its upper and lower portions, said extensions being adapted to engage with said slots and expand 110 said head and foot portions tightly into contact with the track rails.

7. A rail joint of the character described, comprising track rails, a splice bar at each side of the track rails, each splice bar formed 115 with reinforced head and foot portions and having a longitudinal slot therethrough adjacent the head and the foot portions extending the major portion of the length of the bar, said bar having a solid central portion 120 and a recess formed within its outer face, a wedge-shaped member fitted within said recess and its inner face formed with inward extensions at its upper and lower portions adapted to enter said slots and force said 125 head and foot portions tightly into contact with the rail tread and base, respectively, and means for insulating the joint members from the track rails.
